ALPHONSE JULIEN LOISEAU, OF NEW YORK, N. Y.

Letters Patent No. 61,489, dated January 22, 1867.

IMPROVEMENT IN STOP-MOTION FOR LOOMS.

The Schedule referred to in these Letters Patent and making part of the same.

TO ALL WHOM IT MAY CONCERN:

Be it known that I, ALPHONSE JULIEN LOISEAU, of the city, county, and State of New York, have invented a new and improved Stop-Motion for Looms; and I do hereby declare that the following is a full, clear, and exact description thereof, which will enable others skilled in the art to make and use the same, reference being had to the accompanying drawings, forming part of this specification, in which—

Figure 1 represents a longitudinal vertical section of this invention taken in the plane indicated by the line $z z$, fig. 2.

Figure 2 is a horizontal section of the same, the line yy indicating the plane of section.

Similar letters of reference indicate like parts.

This invention relates to an automatic stop-motion which is brought into action whenever one of the warp threads breaks, each warp thread being passed through an eye in the upper end of a short rod, which hangs down through a perforated plate in such a position that it clears a cross-bar which is secured to a pair of oscillating levers secured in the loom-frame, but if one of the warp threads breaks, the appropriate rod drops down and the oscillating cross-bar forces the same against a rod which extends across the loom parallel to the perforated plate, being secured to the upper end of levers which rise from a rock-shaft, from which extends an arm bearing a pusher which serves to press against a spring in the front end of the loom, whenever one of the short rods drops down as above described. The loose end of said spring connects with a dog which catches over one arm of an elbow-lever and holds the same, so that its other arm presses against the catch-bar and prevents the same from being caught by a loop or hook attached to the lay or batten. If the spring is acted on by the pusher, the elbow-lever is released and the catch-bar drops so that the same is carried forward by the action of the lay, and the motion of the loom is stopped either by shifting the belt or by a direct stop.

A represents the frame of my loom, which is made of wood or any other material, and which forms the bearings for the rocking-tree B, to which the lay C is attached. This lay is constructed in the ordinary manner, and it may be made with one or more shuttles, and with one or more openings through which the warp threads pass. On their course from the yarn-beam or spools, to the opening or openings in the lay, the warp threads pass through eyes in the top ends of short rods or weights a, which are freely suspended from said warp threads and pass down through holes in a perforated plate, D. This plate extends across the frame of the loom, being fastened to the same in any suitable manner, and it is perforated with a sufficient number of holes to admit a rod or weight to each warp thread. If the warp threads are stretched at their proper tension, the rods or weights a are raised to such a height that they will not come in contact with a cross-bar, E, towards which they are pressed by the action of a plate, F, which is fastened to vibrating arms G. These arms are suspended from pivots b in the top of the loom, and they receive their motion by eccentrics c, on the driving-shaft H, or in any other suitable manner. The cross-bar E is secured to the top ends of levers, I, which rise from a rock-shaft, J, that has its bearings in the lower part of the frame A, and from this rock-shaft extends an arm, K, to which is attached the pusher L. This pusher terminates in close proximity to a flat spring, M, one end of which is secured to the frame A, while its other loose end connects by a link, d, with a dog, e. If the spring M is in its normal position, said dog catches over one arm j, of an elbow-lever, f, g, which has its fulcrum on a pivot, h, and the other arm, g, of which sustains the catch-bar N. This bar passes freely through a loop or hook, i, secured to the under surface of the lay, and it extends to the back end of the loom, where it connects with an arm, j, rising from a rock-shaft, O, which has its bearings in suitable boxes secured to the frame A. To the arm j is also pivoted the stop k, which may be made to act on a stud, l, projecting from a disk, m, on the driving-shaft, or instead of this the arm j may be connected to the belt-shipper if the loom is driven by power. If one of the warp threads breaks so that the corresponding rod or weight a drops down, the plate F pushes said rod against the cross-bar E, and thereby the pusher L is brought to bear on the spring M. As this spring yields, the dog e is made to release the elbow-lever f, g, and the catch-bar N drops down, so that it is caught by the loop or hook i and carried forward. By this motion of the catch-bar, the arm j is thrown forward and the stop k is brought in such a position that it arrests the motion of the driving-shaft. From the rock-shaft O extends also an arm, m, which connects by a rod, n, with an arm, o, extending from a vertical rock-shaft, p, which has its bearings in suitable brackets secured to the frame A, near to its front. This vertical rock-shaft connects by a

lever, *q*, with a slide, *P*, secured to the breast or front of the loom; and an arm, *r*, extending from the rock-shaft *p*, connects by a pivot, *s*, with the dog *e*. By moving the slide *P* in the direction marked on it in fig. 2, the elbow-lever *fg* is brought in such a position that it prevents the catch-bar *N* from engaging with the loop or hook *i*, but, by moving the slide in the direction opposite to said arrow, the catch-bar is released and the loom is stopped. By this arrangement the automatic stop-motion is combined with the hand stop-motion and the weaver is enabled to stop his loom whenever he pleases. I am aware that automatic stop-motions for looms have been made which operate when the weft thread breaks; this I do not claim.

What I claim as new, and desire to secure by Letters Patent, is—

The oscillating plate *F*, and cross-bar *E*, in combination with the weights or rods *a*, dog *e*, catch-bar *N*, and stop *k*, constructed and operating substantially as and for the purpose described.

The above specification of my invention signed by me this 6th day of October, 1866.

ALPHONSE JULIEN LOISEAU.
